**COMBINED TOY ROCKET PROJECTILE AND
LAUNCHER OR SIMILAR ARTICLE**

Constantin Paul Lent, New York, N. Y.

Application September 15, 1953, Serial No. 26,804

Term of patent 7 years

(Cl. D34—15)

Des. 178,252

PAGE 2

FIG-4

Fig. 1 is a perspective view of a combined toy rocket projectile and launcher or similar article, showing my new design;

Fig. 2 is a front view thereof;

Fig. 3 is a fragmentary top plan view thereof, partly in cross-section with the launcher base folded;

Fig. 4 is a side elevational view thereof.

Fig. 5 is an exploded front elevational view thereof; and

Fig. 6 is a fragmentary bottom perspective view thereof, showing the projectile.

The dominant features of my new design are shown in solid lines in the drawings.

What I claim is:

The ornamental design for a combined toy rocket projectile and launcher or similar article, as shown and described.
